UNITED STATES PATENT OFFICE

2,517,498

AIR CONDITIONING SYSTEM

William Loughney McGrath, Syracuse, N. Y., assignor to Carrier Corporation, Syracuse, N. Y., a corporation of Delaware

Application June 28, 1945, Serial No. 602,002

7 Claims. (Cl. 257—3)

1

This invention relates to air conditioning systems and, more particularly, to systems in which air is tempered under different operating conditions by the circulation of heated or cooled water or other fluid through one or more heat exchangers.

In Carrier Patents Nos. 2,363,294 and 2,363,945, granted November 21, 1944 and November 28, 1944, respectively, there is disclosed an air conditioning system in which a volume of air is conditioned to a desired degree at a central conditioning point, and is then distributed at relatively high static pressure and at relatively high velocity to a plurality of units respectively disposed in and serving a plurality of areas or enclosures to be conditioned. The high pressure air supplied to each unit is discharged therein through nozzle formations or the like, and in this manner induces a relatively great circulation of air withdrawn from the area served by the unit. The primary or conditioned air and the secondary or induced air are then supplied to the area to be conditioned. The primary air may be conditioned at a central conditioning point; and more effective and economical operation is achieved by the delivery of heated or cooled water or other fluid to the various units from a central station preferably to effect sensible cooling or heating of air circulated through the units as required.

In such system, it is necessary to supply some form of control to produce and to maintain desired atmospheric conditions. Carrier Patent No. 2,342,328, granted February 22, 1944, discloses for this purpose a valve structure capable of reflecting changes in air conditions and compensating for variations in such conditions during all seasons of the year. The system so described has been highly successful in commercial operation.

The chief object of the present invention is to provide a simple and modified system of this general type.

An object of the invention is to provide an air conditioning system embodying improved means of supplying conditioning medium to a plurality of air conditioning units disposed in different zones.

A further object is to provide an improved control for an air conditioning unit capable of satisfactory performance under different seasonal operating conditions.

A still further object is to provide an improved control for delivering cooled or heated conditioning medium, automatically as desired, to one or more air conditioning units under different seasonal operating conditions.

2

A still further object is to provide a water circulating system operating under relatively low pressure to govern the flow of conditioning medium of certain character through a control under certain seasonal operating conditions and in which an imposed pressure may be used when medium of other character is employed to change the operation of the control under other seasonal operating conditions.

10 This invention relates to an air conditioning system which includes a unit for conditioning air, a supply of conditioning medium, a passageway or duct for supplying conditioning medium from said supply to said unit, a second passageway or duct into which conditioning medium passes from said unit, and control means in said first passageway responsive to the pressure of the conditioning medium for controlling the circulation of conditioning medium through the unit.

15 Preferably, means are provided for imposing a predetermined pressure on the conditioning medium in the first passageway so that a predetermined increase in pressure may be employed to modify the operation of the control means under various seasonal operating conditions.

20 This invention further relates to an improved control valve for systems of the character described which comprises, in combination, a housing, a change-over element disposed in the housing, means for causing said element to assume one position when conditioning medium under a predetermined pressure is fed to the valve and a second position when conditioning medium under a different predetermined pressure is fed to the valve, a member for opening and closing a passageway from which conditioning medium is discharged from the valve, and means operative responsive to changing conditions in an area being air conditioned for causing said member to tend to change the amount of conditioning medium flowing from the valve.

25 Referring to the drawing illustrating a preferred embodiment of the invention,

30 Figure 1 is a diagrammatic view illustrating the air conditioning system of the present invention;

35 Figure 2 is a sectional view, on an enlarged scale, of the control mechanism included in the system shown in Figure 1; and

40 Figure 3 is a diagrammatic view illustrating a modification of the invention.

45 Referring to Figure 1, there is shown a diagrammatically an air conditioning system including source of supply or receiver 2 for providing to the system a desired volume of conditioning medium, which may be heated or cooled

water or other fluid. A pump 3 sends the conditioning medium to a plurality of air conditioning units 4 through line 5. One or more units 4 may be disposed in different zones of a building such as a hotel or office building, and usually a number of them are placed on different levels or floors of the building, one or more units serving each room or area. In Figure 1 three floors are illustrated on which units 4 are positioned. Control valves 6 are disposed at each unit 4 or in the branch lines 5' leading to each unit and serve to control the circulation of conditioning medium through the units. A return line 7 is provided into which conditioning medium passes from the various units 4 and by which such medium preferably is returned to the source of supply or receiver 2.

A closed expansion tank 8 is disposed in the system to maintain a predetermined pressure upon the conditioning medium in line 5. The pressure imposed by tank 8 upon conditioning medium in line 5 may be varied by means of a compressor or pump 9 connected to a change-over line 10. A thermostat T controls the operation of compressor 9 and may be actuated by means of a thermal responsive element 11 disposed in or in contact with line 5 and, preferably, positioned on the down stream side of pump 3, illustrated.

In Figure 2, there is illustrated the preferred control valve 6 employed in the system. Valve 6 comprises a housing 12 enclosing double-seated valve poppets 13 and 14. An entrance port 15 is provided at one side of housing 12 and an exit port 16 is provided on the other side of the housing. Separate passageways 17 and 18 may be provided through the valve between ports 15 and 16, cooling medium passing through passageway 18 and heating medium passing through passageway 17. The course of cooling fluid is indicated by a dash line while the course of heating fluid is indicated by a dot and dash line. Poppets 13 and 14 control the flow of fluid through passageways 17 and 18, as will herein-after be described. Poppet 13 is actuated by the pressure of the conditioning medium being fed to the valve while poppet 14 is actuated by the temperature of the area or space being conditioned, both serving to control the flow of fluid through passageways 17 and 18 under different seasonal and load requirements.

Valve poppet 13 is attached to a bellows 19 and is actuated by expansion and contraction thereof. A spring 20 is provided in housing 12 adapted to apply a predetermined force or pressure to bellows 19. The pressure or force applied by spring 20 may be adjusted as desired by means of the adjusting screw 21.

The force applied to bellows 19 by spring 20 depends upon the hydraulic pressure maintained in the system. For example, under winter operating conditions, the force applied by spring 20 to bellows 19 is greater than the hydraulic pressure of the conditioning medium so that poppet 13 moves downward seating at the bottom to seal passageway 18 and to open passageway 17; under summer operating conditions the pressure applied to the conditioning medium is greater than the force applied by spring 20 so that poppet 13 moves upward seating at the top to seal passageway 17 and to open passageway 18.

Valve poppet 14 operates similarly to poppet 13 but in response to the temperature of the area being conditioned. A thermostat (not shown) is disposed in the area being conditioned and is

connected to bellows 22 by line 23. A suitable limit regulating control (not shown) is also connected to bellows 22 by line 24. Fluid is disposed in the closed circuit connecting bellows 22, the thermostat and the limit regulating control. As the temperature in the area being conditioned rises, the fluid expands, expanding bellows 22 while upon a decrease in such temperature, the fluid contracts, permitting bellows 22 to contract. Such devices are well-known in the art and form no part of my invention per se. Spring 25 provides a resistance downwardly against poppet 14 opposed to the upward expansive force of bellows 22.

Considering the operation of the system under winter conditions, springs 20 of valves 6 disposed on different floors or building levels will be adjusted for different hydraulic pressures in line 5. For example, referring to the system shown in Figure 1, spring 20 of the upper valve 6 (on the top floor) may be adjusted to resist a hydraulic pressure of conditioning medium of 15 pounds per square inch; spring 20 of the intermediate valve 6 may be adjusted to resist a pressure of conditioning medium of 25 pounds per square inch and spring 20 of the lower valve 6 (on the bottom floor) may be adjusted to resist a pressure of conditioning medium of 35 pounds per square inch. Thus, assuming the pressure of the conditioning medium is less than the amounts given at the various floors, poppets 14 will be moved downwardly by springs 20 and open passageways 17 through the respective valves for the passage therethrough of heated conditioning medium.

Depending upon the temperature of the area being conditioned, poppet 14 will open or close passageway 17 to the heated conditioning medium. Assuming the thermal responsive element disposed in the area being conditioned reflects a cool condition therein, the fluid in bellows 22 will be contracted, permitting spring 25 to move poppet 14 downward opening passageway 17 to the heated conditioning medium and permitting its flow to the conditioning coils of the various units 4. As the temperature in the area being conditioned rises, bellows 22 will expand, moving poppet 14 upward against the resistance of spring 25 and partially or completely closing passageway 17.

Under summer operating conditions, an increase in static pressure of predetermined amount is imposed on conditioning medium in line 5 by means of compressor 9 and expansion tank 8. Such increase in pressure must be sufficient to force the poppets 13 upward against the resistance of springs 20 thus closing passageways 17 and opening passageways 18. Increase of pressure is controlled by thermostat T operating pressure control P (shown in dotted outline) which actuates compressor 9. Thermostat T is actuated by thermal responsive element 11 which reflects the temperature of conditioning medium in circuit 5. If the temperature of conditioning medium in line 5 is below a predetermined point, the compressor is actuated to impose increased pressure therein, say 10 pounds greater than under winter operating conditions.

Under summer operating conditions poppet 14 may be actuated to open or to close passageway 18. If the temperature in the area being conditioned reflects a warm condition, poppet 14 is forced upward by bellows 22 opening passageway 18. As the temperature in the area being conditioned decreases, bellows 22 contracts, permit-

ting spring 25 to move poppet 14 downward thus closing or partially closing passageway 18. As described above, poppets 13 and 14 are automatic in operation, poppet 13 being operable in response to the pressure of conditioning medium in the system and poppet 14 being operable in response to the temperature of the area being conditioned.

In Figure 3, I have illustrated a modified system generally similar to the system shown in Figure 1. In the system partially shown in Figure 3, an open expansion tank 26 is employed and compressor 9 may be eliminated. The tank 26 is connected to change-over line 10 and the pressure imposed upon the conditioning medium in line 5 is determined by the level of conditioning medium maintained in tank 26. A float valve 27 maintains a certain level when under summer operating conditions to impose required pressure on conditioning medium while float valve 28 maintains a certain level under winter operating conditions, also imposing a predetermined pressure on the conditioning medium different than that imposed under summer operating conditions.

While I have described the system as requiring an increase in hydraulic pressure under summer conditions, it will be appreciated that a decrease in hydraulic pressure may be employed under such conditions; in such case, the valve 6 may be modified accordingly with the position of the temperature responsive element being reversed in order that the heated or cooled conditioning medium may flow in different paths. Such modification is contemplated by my invention and may be made without departing from the scope thereof.

My invention provides an improved air conditioning system in which a change-over from winter to summer operating conditions is controlled by the hydraulic pressure of the conditioning medium which flows through the conditioning units of the system. The conditioning system is less complicated than systems heretofore used and is at least as economical in installation and operation costs. The unit controls provided are simple and actuatable by the pressure of the conditioning medium. The system operates satisfactorily under both winter and summer conditions and may be modified if desired to provide either heating or cooling in any season of the year to various zones with the result that any desired tempering may take place at any point of distribution.

While I have described a preferred embodiment of my invention, it will be understood my invention is not limited thereto since it may otherwise be embodied within the scope of the following claims.

I claim:

1. In a system of the character described, the combination of a plurality of units for conditioning air, a supply of conditioning medium, a passageway for supplying conditioning medium from said supply to said units, means for imposing a predetermined pressure on the conditioning medium in said passageway, and a plurality of valves in said passageway for controlling the circulation of conditioning medium through said units, at least one of said valves including a change-over element responsive to pressure of conditioning medium entering the valve, means for changing the pressure imposed on the conditioning medium in said passageway, means for causing said element to assume a first position said element being adapted to assume a second position in response to a predetermined change in the pressure of the conditioning medium, a device for opening and

closing a passageway from which conditioning medium is discharged from the valve, and means for operating said device in response to changing conditions in an area being air conditioned.

5 2. A system according to claim 1, in which said device tends to reduce the flow of conditioning medium from the valve when said element is in the first position and the temperature in the area being conditioned tends to rise above a desired level and is adapted to tend to increase the flow of fluid from the valve when said element is in the second position and the temperature in such area tends to rise above a desired level.

10 3. In a system of the character described, the combination of a plurality of units for conditioning air, a supply of conditioning medium, a passageway for supplying conditioning medium from said supply to said units, a second passageway for returning conditioning medium to said supply after it has passed through said units, an expansion tank connected to said first passageway for imposing a predetermined pressure on conditioning medium therein, means for imposing a predetermined pressure on conditioning medium in said tank, a valve at each unit for admitting conditioning medium to the unit, means in each valve for closing a port therein under a predetermined pressure of conditioning medium and opening said port under an increase in said predetermined pressure of the conditioning medium, and means in each valve responsive to the temperature of the area being conditioned for metering the volume of fluid passing through the valve.

15 4. A system according to claim 3 in which an open expansion tank is employed, the pressure imposed upon the conditioning medium being predetermined by float valves in said tank for maintaining a desired level of conditioning medium therein.

20 5. In a system of the character described, the combination of a plurality of units for conditioning air, a supply of conditioning medium, a passageway for supplying conditioning medium from said supply to said units, a second passageway for returning conditioning medium to said supply after it has passed through said units, an expansion tank connected to said first passageway for imposing a predetermined pressure on conditioning medium therein, means for imposing a predetermined pressure on conditioning medium in said tank and a valve at each unit for admitting conditioning medium to the unit, said valve comprising a change-over element responsive to pressure of conditioning medium entering the valve, means for causing said element to assume a first position, said element being adapted to assume a second position in response to a predetermined change in the pressure of the conditioning medium, a device for opening and closing a passageway from which conditioning medium is discharged from the valve, and means for operating said device in response to changing conditions in an area being air conditioned.

25 6. In a system of the character described, the combination of a plurality of units for conditioning air, a supply of conditioning medium, a passageway for supplying conditioning medium from said supply to said units, a second passageway for returning conditioning medium to said supply after it has passed through said units, an expansion tank connected to said first passageway for imposing a predetermined pressure on conditioning medium therein, means for imposing a predetermined pressure on conditioning medium in said tank, and a conditioning medium flow

regulating device at each unit for regulating the circulation of conditioning medium through the units, said device comprising a first valve, means for retaining said valve in a first position, said valve being movable to a second position in response to an increase in pressure of conditioning medium flowing through the valve, a second valve, and means responsive to changing conditions in an area being air conditioned for changing the position of said second valve to meter the amount of conditioning medium flowing through the valve.

7. In a system of the character described, the combination of a plurality of units for conditioning air, a supply of conditioning medium, a passageway for supplying conditioning medium from said supply to said units, a second passageway for returning conditioning medium to said supply after it has passed through said units, an expansion tank connected to said first passageway for imposing a predetermined pressure on conditioning medium therein, means for imposing a predetermined pressure on conditioning medium in said tank, and a control valve at each unit for regulating the circulation of conditioning medium through the units, said valve including a first upper passage, a first lower passage, a second upper passage, a second lower passage, means

for admitting a first conditioning medium to the valve, means operative responsive to the pressure of said conditioning medium for causing one of said first passages to be open and the other to be closed, second means for causing one of said second passages to be open and the other second passage to be closed, and a temperature responsive element for actuating said second means in response to changing temperature conditions in an area being air conditioned.
